CLOCK

Ben Lerman, Chicago, Ill., assignor to Master-crafters Clock & Radio Company, Chicago, Ill., a corporation of Illinois

Application March 25, 1949, Serial No. 1,619

Term of patent 14 years

(Cl. D42—7)

To all whom it may concern:

Be it known that I, Ben Lerman, a citizen of the United States of America and resident of the city of Chicago, county of Cook, and State of Illinois, have invented a new, original, and ornamental Design for a Clock, of which the following is a specification, reference being had to the accompanying drawing, forming a part thereof.

Fig. 1 is a front elevational view of a clock, showing the essential features of my design in full lines.

Fig. 2 is a back elevational view thereof.

Fig. 3 is an elevational view of the clock looking at it from one side.

I claim:

The ornamental design for a clock, substantially as shown and described.

BEN LERMAN.
